UNITED STATES PATENT OFFICE.

CHARLES M. GREISING AND WALTER E. NAYLOR, OF ST. PAUL, MINNESOTA, ASSIGNEES, BY MESNE ASSIGNMENTS, TO INTERNATIONAL HARVESTER COMPANY, A CORPORATION OF NEW JERSEY.

MEANS FOR CONTROLLING FIBER-TREATING MACHINES.

1,291,644.

Specification of Letters Patent. Patented Jan. 14, 1919.

Application filed October 8, 1913. Serial No. 794,137.

To all whom it may concern:

Be it known that we, CHARLES M. GREISING and WALTER E. NAYLOR, citizens of the United States, and residents of St. Paul, in the county of Ramsey and State of Minnesota, have invented certain new and useful Improvements in Means for Controlling Fiber-Treating Machines, of which the following is a full, clear, and exact specification.

This invention relates to mechanism for removing waste particles from fiber or other material out of which twine is made, and more particularly to means for controlling the operation for such mechanism.

In the manufacture of twine the fiber or other material out of which twine is made is passed through various preparing, spinning and balling machines. While being fed into and in passing through such machines pieces of fiber fall from the machines and collect on the floor. At the same time more or less dust is liberated from the fiber as it passes through such machines. Most of this dust is drawn out through a suitable exhaust system, but some of the dust collects on the floor and becomes mixed with the fiber which has fallen onto the floor around and under such machines. Were this dust laden fiber thrown away, immense financial loss would result. To avoid such financial loss and to use all of the fiber, this dust laden fiber is gathered from the various machines and put through a cleansing process in which all of the dust is removed from the fiber. The mechanism used for removing the dust includes a shaker and a picker. Shakers and pickers have been used for some time, but have been operated in such a way that fiber which has not been thoroughly cleaned has been tossed into the picker from the shaker at a time and in many instances when the picker was not in the proper stage of operation to receive such fiber. In other words, the picker would receive the dust laden fiber from the shaker and discharge same without completing the cleansing process of the fiber. Under these conditions the fiber might not and more likely would not pass out of the picker in a clean condition. The fault resided in the fact that the operation of the coöperative shaker and picker was not properly controlled.

It, therefore, is the object of our invention to control the operation of coöperating shakers and pickers in a manner such that the fiber passing through such shakers and pickers will be thoroughly cleaned before passing from the latter.

This object is accomplished by providing in combination a shaker, a picker, and means for controlling the operation of said shaker and picker in a manner to obtain the desired result.

The invention is illustrated on the accompanying sheets and drawings in which—

Figure 1 is a side elevation of a picker and a portion of a shaker embodying our invention;

Fig. 2 is a fragmentary side elevation of the same shaker;

Fig. 3 is a plan view of the shaker, picker, and control mechanism shown in elevation in Fig. 1;

Fig. 4 is a side elevation of the control mechanism proper;

Fig. 5 is an end view of the same, parts being shown in section;

Figs. 6 and 7 are side and end elevations respectively of a cam member forming a part of the control mechanism shown in Figs. 4 and 5;

Fig. 8 is a sectional view of part of the transmission system by means of which motion is transmitted to the control mechanism; and

Fig. 9 is a plan view of one end of the shaker showing means for conveying dust laden fiber to the shaking members, and means for controlling the quantity of supply of said fiber to said shaking members.

The various novel features of our invention will be apparent from the description and drawings, and will be particularly pointed out in the appended claims.

The mechanism herein considered, generally speaking, includes a shaker 10, picker 11, and control mechanism 12 associated with the picker 11 for controlling the operation of said shaker and picker. The shaker (reference being had particularly to Fig. 2) includes a box-like structure 13 in which two shaking members 14 and 15 are actuated, said shaking members taking the form of movable grates through which dust may pass from fiber or material shaken thereon. The shaking member 14 is actuated by means of

beams 16 pivotally connected at one end to shaking member 14 and at the other end connected with an actuating shaft 17 by means of eccentrics 18. As the shaft 17 rotates the 5 shaking member 14, which is supported by rods 19 pivoted to the main frame at 20, is given a reciprocatory motion. In a similar manner the shaking member 15 is actuated, the only difference being that the shaking 10 member 15 is located beyond and below the first shaking member 14. The actuating shaft 17 is provided with a loose pulley 21 and a tight pulley 22, which are alternatively engaged by a belt 23 connecting said 15 pulleys with any suitable driving source. The shaft 17 is also provided with a pulley 24 around which passes a belt 24^a, which is crossed and passes over another pulley 25 mounted upon one end of a shaft 26, upon 20 the other end of which is secured a gear wheel 27 meshing with a relatively large gear 28, the latter being mounted upon one end of a shaft 29, to the other end of which is secured a sprocket wheel 30. Passing 25 around said sprocket wheel 30 is a chain 31 which passes over another sprocket wheel 32 mounted upon one end of a shaft 33 upon which is mounted a feed controller or kicker 34 which is adapted to control the quantity 30 of supply of dust laden fiber deposited in a pit portion 35 and conveyed therefrom past said feed controller and upon a conveyer band 36 to the first shaking member 14. This conveyer band 36 passes around a roller 35 37 and a roller 38, the latter of which is mounted upon the shaft 29. The feed controller 34 which rotates in a counter clockwise direction, as viewed in Fig. 2, may be adjusted with respect to the conveyer band 40 by any suitable mechanism 40 to vary the quantity of supply of dust laden fiber fed from pit 35 onto the shaking member 14. When the belt 23 is on the tight pulley 22, the shaking members 14 and 15 therefore 45 being actuated, dust laden fiber which has been deposited upon the shaking member 14 is shaken or vibrated thereon for removing dust from said fiber. This shaking movement of the member 14 causes the fiber 50 to be tossed gradually along the grating of member 14 toward the shaking member 15 upon which it is eventually deposited to be shaken further. Dust which has been shaken from the fiber falls upon the floor 41 of the 55 shaker and is scraped therefrom by a conveyer 42 into a pit 43 in which a conveyer screw 44 is actuated from any suitable source for carrying away the dust to a furnace (not shown). The conveyer 42 includes 60 chain members 45 which pass over a gear wheel 46 mounted upon the shaft 47 at one end of the shaker 10 and over another gear wheel 48 mounted upon a shaft 49 at the extreme opposite end of the picker 11. Motion 65 is transmitted to this conveyer 42 by

means including a sprocket wheel 50 mounted upon one end of shaft 49, a chain 51 passing over said sprocket wheel and another sprocket wheel 52 mounted upon a stud shaft 53, upon which also is mounted a pulley 54 70 which may receive motion from any suitable source.

The picker 11 proper includes two rotatively mounted wheels 55 provided with pins or spikes 56 which carry the fiber around for 75 beating dust out of the same. These wheels are mounted upon shafts 57 and are rotated in opposite directions by means of a crossed belt 58 which passes over pulleys 59 and 60 mounted on said shafts, one of said shafts 80 having a pulley 61 which is adapted to receive motion from any suitable driving source. Mounted below the picker wheels 55 is a curved grating 62 through which dust passes and is conveyed away by the same 85 conveyer 42 to the conveyer screw 44. The picker is provided with a door 63 (see Figs. 3, 4 and 5), through which the fiber passes after it has had all of the dust removed therefrom. After passing through this door 90 the fiber is deposited upon a conveyer band 64 which is driven by any suitable means 64^a for carrying away the cleaned fiber. This fiber after passing through this dust removing process may be made up into 95 twine.

From the arrangement thus far described it is seen that fiber picked up from around the various fiber treating machines is thrown into the pit 35, carried into the shaker by 100 conveyer band 36, the fiber shaken on shaking members 14 and 15 from which it is passed automatically, by the thrusting action of shaking member 15, into the picker 11 where all remaining dust is removed, 105 after which the fiber passes through the picker door 63 onto the conveyer 64, from which it may be collected to be made up into twine.

Heretofore there has been no accurate and 110 well-timed relation between the operation of the shaker and the opening and closing of the picker discharge door 63. Due to this fact, in many instances dust laden fiber from the shaker has been passed into the picker 115 at the time the discharge door was opened, resulting in the discharge of fiber from which the dust has not been thoroughly removed. To overcome this undesirable feature, we have provided the shaker and picker with timing and control mechanism which 120 operates in a manner such that the shaker is permitted to operate only at a time when the discharge door of the picker is closed, the opening and closing of the picker discharge door and the operation of the shaker being controlled automatically. This control mechanism includes a relatively large gear 65 which meshes with a smaller gear 66, mounted upon a stud shaft 67 upon which 130

also is mounted a sprocket wheel 68 over which passes a chain 69 which is actuated by a sprocket wheel 70 mounted upon one end of shaft 49. The gear wheel 65 is secured to 5 a sleeve portion 71 of a cam member 72 having an internal cam surface 73 which is engaged by a roller 74 mounted in one end of an arm 75, which arm is secured to a shaft 76 mounted in bearing members 77 secured 10 to the frame of the picker 11. Secured to the shaft 76 are two arms 78 each having a yielding connection to the discharge door 63 by means of slotted links 80 and resilient members or springs 81. As shown in Fig. 4 15 during three-quarters of a revolution of the cam member 72 the roller 74 takes a circular path, during which time the door 63 is maintained in a closed position, and during the other quarter of the revolution of the cam 72 20 the roller 74 engages the elongated portion 72^a of said cam, during which time the discharge door 63 is being opened and closed. Also secured to the sleeve 71 of the cam member 72 is a second cam 82 (see Figs. 4, 5, 25 6 and 7), the surface of which is engaged by a roller 83 mounted in one end of a pivotally mounted lever 84, to one end of which is connected a link 85, which is connected to a belt shifter 86 through the medium of an arm 87, rod 88 and arm 89. The belt shifter 30 is provided with the usual projecting member 90 for engaging the belt 23. To the shifter is connected a spring 91 tending to shift the belt onto the tight pulley 22 and to 35 force the roller 83 into the notched portion 92 of the cam 82. It is to be noted that the notched portion of the cam occupies about one-fourth of the periphery of the cam 82, corresponding to the relative duration of 40 operation of the shaker, the remaining three-fourths of the periphery of the cam 82 being circular. When the roller 83 passes into the notched portion 92 of cam 82 the belt shifter is caused to shift the belt onto the tight pulley 22, whereupon the shaking members 14 45 and 15 are actuated until the roller 83 passes out of the notched portion and onto the circular part of the cam 82. By referring particularly to Fig. 4 it will be noted that 50 with the cams 72 and 82 in their full line positions, the picker discharge door 63 is opened and that as the roller 74 passes upwardly on the right hand side of the elongated cam portion 73 the roller 83 will approach the notched portion 92 of the other cam 82. Just at the point where the roller 74 reaches the circular part of cam 72, at 55 which time the discharge door 63 has been completely closed, the roller 83 passes into 60 the notched portion 92 of cam 82, at which time the shaker is started into operation. This position of the cams is shown in dotted lines in Fig. 4. As above stated, the shaker continues in operation during the following 65 quarter revolution of the cams 72 and 82, during which time the fiber is transferred automatically from the shaker into the picker, the wheels 55 of the picker being operated continuously for removing any dust which may be in the fiber. During the 70 following half revolution of the cams 72 and 82 the shaker is held in a state of rest and the discharge door 63 of the picker is held closed, the picker wheels 55, however, being continuously in motion. At the end of this 75 last half revolution the roller 74 has reached a point 93 on the cam 72, at which point the roller 74 is about to drop down the elongated portion of the cam 72 due to the weight of the arm 75 for opening the discharge door 80 80 85 85 90 90 95 95 100 100 105 105 110 110 115 115 120 120 125 125 130 130

By means of this control mechanism which is associated with the picker, it is seen that the shaker is caused to operate intermittently at times only when the discharge door of the picker is closed, and the opening and closing of the discharge door of the picker and the operation of the shaker are automatically controlled. In this manner it is impossible for fiber to pass through the discharge door 63 without first having the dust thoroughly removed therefrom. It is to be noted that due to the belt connection 24^a the feed controller 34 is controlled simultaneously with the shaker proper; that is, when the shaker is in operation the feed controller is in operation and when the shaker is at rest the feed controller is at rest.

It is apparent that there may be various modifications of our invention as particularly herein described and shown, and it is

our intention to cover all such modifications which do not involve a departure from the spirit and scope of our invention as set forth in the appended claims.

5. What we claim as new is:

1. In combination, a fiber treating member, a receptacle in which fiber is treated having a discharge door, means for controlling the operation of said fiber treating member and the opening of said door, and separate means for positively opening said door if said door becomes wedged.

10 2. In combination, an oscillatory cleaner, a cleaning chamber into which the fiber may be deposited from said oscillatory cleaner, said chamber having a rotary picker therein, and having an exit door through which the fiber may pass, means for moving said door, operating means for said oscillatory cleaner, and unitary control means for controlling said operating means and said door moving means.

15 3. In combination, fiber cleaning means including means for agitating and feeding the fiber, a receptacle into which the fiber may be deposited from said member, said receptacle having picker mechanism therein and having an opening through which the fiber may be discharged, means for operating said fiber cleaning means, a door for said opening to normally prevent discharge of the fiber therethrough, and a control member for controlling the intermittent operation of the fiber cleaning means and intermittent operation of the door.

20 4. In combination, an oscillatory fiber cleaning member, a receptacle disposed in a position to receive the fiber from said cleaning member, said receptacle having picker mechanism therein and having an opening through which the fiber may be discharged, a feed controller for controlling the quantity of material fed to said fiber cleaning member, means for operating the feed controller and the oscillatory cleaning member, a door for said opening to normally prevent the

passage of fiber therethrough, and a member for controlling said operating means and the movement of said door.

5. In combination, an oscillatory fiber 50 cleaning member, a receptacle disposed in a position to receive the fiber therefrom, said receptacle having picker mechanism therein and having an opening through which the fiber may be discharged, a door disposed in 55 said opening, a cam for controlling the operation of the fiber cleaning member, and a cam for controlling the operation of said door.

6. In combination, fiber cleaning means 60 having mechanism for agitating and imparting an intermittent forward movement to the fiber, a receptacle disposed in a position to receive the fiber from said cleaning means, said receptacle having picker mechanism therein and having an opening through which the fiber may pass, a door disposed in 65 said opening, and two cams working in timed relationship, one operatively connected to the cleaning means for controlling the 70 operation thereof and the other operatively connected to the door controlling the operation of the latter.

7. In combination, fiber cleaning means including mechanism for shaking the fiber, 75 a receptacle disposed in a position to receive the fiber from said cleaning means, said receptacle having picker mechanism therein and having an opening through which the fiber may pass, a door disposed in said opening, means for yieldingly holding said door in closed position, and cam means for controlling the operation of said fiber cleaning means and the operation of said door.

In testimony whereof we affix our signatures, in the presence of two witnesses.

CHARLES M. GREISING.
WALTER E. NAYLOR.
